CLAIMThe ornamental design of a vacuum cleaner upper portion,
as shown and described.**DESCRIPTION**FIG. 1 is a front elevational view of a vacuum cleaner upper
portion showing our new design;

FIG. 2 is a top view thereof;

FIG. 3 is a left side elevational view thereof;

FIG. 4 is a right side elevational view thereof;

FIG. 5 is a rear elevational view thereof;

FIG. 6 is a front elevational view of a second embodiment
thereof; and,

FIG. 7 is a left side elevational view of thereof.

The top, right side elevational, and rear elevational views of
the second embodiment being identical to FIGS. 2, 4, and 5,
respectively, and the dot-dash ghost line portions in FIGS. 1
and 2 being for the purpose of environment only and form
no part of the claimed design.**1 Claim, 3 Drawing Sheets**FIG. - 2
